UNITED STATES PATENT OFFICE.

CLINT HAMMOND AND WILLIAM INMAN, OF BOYNE CITY, MICHIGAN, ASSIGNEES OF ONE-THIRD TO SAID INMAN AND TWO-THIRDS TO HYLON J. HEATON AND SABIN HOOPER, OF BOYNE CITY, MICHIGAN.

ACCELERATOR.

Application filed July 5, 1921. Serial No. 482,481.

To all whom it may concern:

Be it known that we, CLINT HAMMOND and WILLIAM INMAN, citizens of the United States, and residents of Boyne City, in the county of Charlevoix and State of Michigan, have invented certain new and useful Improvements in Accelerators, of which the following is a full, clear, and exact description.

10 This invention relates to accelerators, especially adapted for use on internal combustion engines.

Briefly stated an important object of this invention is to provide an accelerator for 15 Ford motors having means whereby the same is operated automatically by the depression of either the clutch or reverse pedals.

A further object is to provide an accelerator for internal combustion engines 20 which may be applied to the engine without elaborately altering the construction of the same and which will effect an appreciable economy in the consumption of fuel.

25 Other objects and advantages of the invention will be apparent during the course of the following description.

In the accompanying drawing forming a 30 part of this application, and in which like numerals are employed to designate like parts throughout the same.

Figure 1 is a plan view of the improved accelerator applied, and

35 Figure 2 is a perspective view of the same detached.

In the drawing wherein for the purpose of illustration is shown a preferred embodiment of the invention, the numeral 5 designates an internal combustion engine having a carburetor 6 which in this case is controlled by an accelerator generally designated by the numeral 8.

As is well known the Ford motor is 45 equipped with a planetary transmission, having a high and low speed or clutch pedal 10, and reverse pedal 11. In use the low speed pedal 10 is depressed to throw the transmission into low speed and by increasing the pressure on the low speed pedal the 50 transmission band operated by the same is tightened for providing a firmer driving connection between the engine and the shaft. On the other hand when the reverse pedal 11 is depressed the vehicle operated by the

internal combustion engine 5 is reversed and 55 in this case also by increasing the pressure on the pedal 11 the driving connection between the engine and the rear wheel is tightened.

The improved accelerator is formed from 60 a length of round metal having one end portion formed with a bend 12 defining a U-shaped member. The said U-shaped member thus formed is provided with an arm 14 rotatably connected to the transmission housing by means of a pair of spaced clips

16. The other arm 17 of the U-shaped member formed by the bend 12 has that portion adjacent the bend 12 arranged directly in advance of the pedals 10 and 11. Therefore, when the pedals 10 and 11 are depressed when throwing the transmission either in low speed or reverse, the pedal 65 engaging portion 20 of the arm 17 will be moved downwardly in a clockwise direction, moving the entire rod in the same direction.

The arm 17 at one side of the U-shaped member is formed with an offset, disposing the terminal portion of the arm above the 70 pedal-engaging portion 20 and defining the foot contact portion 24. By offsetting the foot-engaging portion 24 with respect to the pedal-engaging portion 20 more accurate control over the carburetor may be exercised by the foot. In other words, the foot- 75

engaging portion is rendered less sensitive than would be the case if the same was in line with the pedal-engaging portion 20. 80

The other end of the rod is offset, as indicated at 26, to define an attaching arm 90 95 95 to which a link 30 is connected. The forward end of the link 30 is extended laterally, as indicated at 32, and is connected to the throttle arm 34 over the carburetor. A coil spring 35 is connected to the attaching arm 28 of the accelerator and serves as a means for normally holding the accelerator in an inoperative position.

In operation either the pedal 10 or the 100 105 105 pedal 11 is depressed so as to engage the pedal-engaging portion 20, whereby the rod may be rotated in a clockwise direction for opening the main valve of the carburetor. Should it be desired to reverse the vehicle the pedal 11 is depressed and as the driving connection between the engine and the rear wheels is tightened the engine is accelerated automatically. The same applies

to the operation of the low speed pedal 10 which is depressed for throwing the transmission into low speed.

The pedal-engaging portion 20 is braced 5 by means of a transversely extending rod 38 welded or otherwise secured at its ends to the arms formed by the bend 12. A second brace 40 is secured to the rod at opposite sides of one of the bearing members 10 16 and serves to strengthen the rod at the offset 42 in the same.

With reference to the foregoing description taken in connection with the accompanying drawing it will be apparent that 15 a foot accelerator constructed in accordance with this invention will be automatically operated when the foot pedals 10 and 11 are depressed. Also the foot-engaging portion 24 is within convenient reach of the 20 operator and will not interfere with the operation of the brake 46 since the offset in the arm 17 disposes the foot-engaging portion 24 rearwardly of the brake pedal.

We claim:

25. 1. An accelerator formed from a length of metal formed with a bend defining a pair of arms, one of said arms being formed with an offset defining pedal and foot-engaging portions, and attaching means associated with the other arm.
2. An accelerator formed from a length of metal formed with a bend defining a pair of arms, one of said arms being formed with an offset defining pedal and foot-engaging portions, attaching means associated with the other arm, and bracing means between said arms.
3. An accelerator formed from a length of metal formed with a bend defining a pair of arms, one of said arms being formed with an offset defining pedal and foot-engaging portions, attaching means associated with the other arm, and spring means normally holding said pedal and foot-engaging portions in their inoperative positions.
4. An accelerator for internal combustion engines comprising a pair of arms, one of said arms being formed with an offset portion defining a foot and a pedal-engaging portion, said offset also disposing said foot-engaging portion in spaced parallel relation to said pedal-engaging portion, and an operating link connected to one of said arms.
5. An accelerator for internal combustion

engines comprising a length of metal 55 formed intermediate its ends with a bend defining a pair of spaced parallel arms having offsets, one of said offsets defining a foot-engaging portion and a pedal engaging portion, a bracing device connected to 60 one of said arms at opposite sides of the offset in the same, means rotatably supporting one of said arms, and an operating member connected to one of said arms.

6. An accelerator for motor vehicles comprising a pair of spaced arms, one of which is adapted to be directly engaged by a plurality of the foot pedals of a planetary transmission, and means to rotatably support the other arm, said arms being arranged in parallel relation and transversely 70 of the motor vehicle.

7. An accelerator for motor vehicles comprising a pair of arms, one of which is adapted to be engaged by certain of the foot 75 pedals of a planetary transmission, and means to rotatably support the other arm, one of said arms being formed with a bend defining a foot engaging portion.

8. An accelerator for motor vehicles comprising a pair of arms, one of which is adapted to be engaged by certain of the foot 80 pedals of a planetary transmission, and means to rotatably support the other arm, one of said arms being formed with a bend 85 defining a foot engaging portion, and the other arm being formed with means whereby the same may be connected to a carbureter.

9. An accelerator for motor vehicles comprising a length of metal formed with a bend defining a pair of arms, one of which is adapted to be engaged by certain of the foot 90 pedals of a transmission, and means whereby to rotatably support the other arm. 95

10. An accelerator comprising an arm having its intermediate portion offset whereby to provide pedal and foot engaging portions, the pedal and foot engaging portions being arranged in parallel relation. 100

11. An accelerator comprising an arm having its intermediate portion offset whereby to provide pedal and foot engaging portions, and means associated with said arm for supporting the same and connecting the arms to a carburetor. 105
